UNITED STATES PATENT OFFICE.

GEORGE C. LASARES, OF SPRINGFIELD, MASSACHUSETTS.

TOY BOWLING GAME.

1,321,108.

Specification of Letters Patent. Patented Nov. 11, 1919.

Application filed December 27, 1918. Serial No. 268,459.

To all whom it may concern:

Be it known that I, GEORGE C. LASARES, a citizen of the United States of America, residing in the city of Springfield and county 5 of Hampden and State of Massachusetts, have invented certain new and useful Improvements in Toy Bowling Games, of which the following is a specification.

This invention relates to improvements in 10 toy bowling games and particularly that part of the game which relates to the target.

The object of the invention is to provide a movable target which is adapted to be automatically operated when a ball is rolled 15 along the floor. The invention comprises a series of movable members bearing figures representing persons or any suitable objects, that are mounted upon a common support with means for setting or moving all of 20 the members into a position to be automatically tipped or moved into another position by means of mechanism that is operated when the rolled ball strikes certain parts of the operating mechanism.

25 Referring to the drawings:

Figure 1 is a front elevational view of the target device showing the figures in the position they occupy after the ball has been rolled, or the inoperative position;

30 Fig. 2 is a sectional view on the line 2—2 of Fig. 1 showing the movable members on which the figures are placed, in the inoperative position and illustrating the construction of the movable members;

35 Fig. 3 is a detail view of the target similar to Fig. 2 showing the movable members in the set position; and

Fig. 4 shows the target in the position the parts occupy at the moment the rolled ball 40 strikes the operating mechanism to throw the movable members into the inoperative position shown in Figs. 1 and 2.

Referring to the drawings in detail: 1, 2, and 3 designate the side and end members 45 composing the framework of the target, 4 and 5 are two rods arranged in parallel relation to each other and fixedly secured to the end pieces 1 and 2 by any suitable means. 6 designates a wire that is also arranged in 50 parallel relation to the rods 4 and 5. This wire is preferably secured at its ends in the pieces 7 and 8 which are secured to the ends 1 and 2. Loosely mounted on this wire are the spacing pieces 9 and 10 for separating 55 the movable members 11. These members are formed with a longitudinal groove 12

therein to receive the ball 13 which is smaller than the groove to permit it to roll freely from one end of the groove to the other. The ball is prevented from escaping by 60 means of the pins 14. The pivotal point 11' of the member 11 is such that in its set position, as shown in Fig. 3 the ball 13 rolls to the upper end or long arm part of the member 11, or, in other words the member 65 11 is overweighted in order to retain the same in its set position. In order to tip the same forward into its inoperative or normal position striking devices are provided which consist of pendant members 15 70 shaped like ten-pins, which are loosely hung on a wire 16. 17 are hollow spacing pieces on the wire 16 for maintaining the pendant members properly spaced from each other. 18 designates striking rods that are freely 75 and slidably mounted in openings in the rods or bars 4 and 5, the lower ends of which are struck by the pendant members 15 when a rolled ball 19 strikes one of the pendant members and forcibly moves the 80 same into the position shown in Fig. 4, from the normal position of the pendant members shown in Figs. 1 and 2. As the rod 18 is moved suddenly upward in the direction of the arrow 19' in Fig. 4 its upper end will 85 strike the upper end of the movable weighted members 11 causing the same to be tilted forward into its normal position shown in Figs. 1 and 2. The ball then rolls downward in the groove 12 until it strikes the 90 pins 14.

For the purpose of simultaneously setting the members 11 with the attached figures 20, 21, and 22 that consist of lithographs, printed on paper, and pasted to the pieces 95 23, a rotatable rod 24 having an operating knob 25 is provided. This rod is located below the pivotal point 11' of the member 11 and is provided with pins 26 which, as the rod 24 is turned in the direction of the 100 arrow 27 will engage the lower or rear side of the members 11 causing these members to be simultaneously tilted upward from the position shown in Fig. 2 to that shown in Fig. 3. When a rolled ball 19 strikes a 105 pendant member 15 the rod 18 strikes the upper rear end of the member 11 causing it to be thrown or tilted downward into its normal position shown in Figs. 1 and 2; the arrow 28, Fig. 4 indicates the direction of 110 the movement of the member 11 and its attached figure. The numerals "3", "2" and

"5" on the figures 20, 21 and 22 shown in Fig. 1 indicate the value of the hit made by the player when a successful throw of the ball 19 operates to cause the movement of 5 one of the figures from its set position shown in Fig. 3 to that shown in Fig. 1.

It will be seen that the present invention is one that can be readily and easily operated by unskilled players. The opening 29 serves 10 to permit the rolled balls to pass through the frame.

The rods 18 slide very freely in the rods 4 and 5 and are provided with stop pins 18' to limit their upward and downward movements in the supporting rods 4 and 5. In 15 Fig. 4 the rolled ball is shown as passing through the opening 29 of the main framework.

What I claim is:

20 1. A device of the kind described, comprising a frame-work, members tiltably supported therein, means for retaining said members in nearly a horizontal position when in their set positions, means for tilt- 25 ing the members into an inclined or nearly vertical position, means for retaining the same in said latter mentioned positions, means for causing the members to be moved into the vertical positions, said 30 last mentioned means comprising pendant members, slidable rods in the path of the pendant members, one end of the rods being arranged to engage the tilttable members and cause the same to be moved into their vertical 35 cal positions, as described.

2. A movable member for a bowling game and having a groove therein to receive a movable weight, as a ball, said member being pivotally mounted at a point thereof 40 distant from its center point to provide an arm that is longer than the other, whereby as the ball rolls into a position onto the longer arm the member will be tipped into an inclined position and in stable equilibrium, a slidable rod for maintaining the member in this position and, when the ball 45 passes its center of support in the opposite direction the movable member will be in its normal position.

50 3. A bowling game device comprising a framework, a member bearing a figure mov- ably mounted therein, the member being supported at a point distant from its central point to provide an overweighted arm, a 55 slidable rod the upper end of which serves to support the member in its set position, a pendant member for operating the slidable rod, whereby when the slidable rod is operated the longer arm of 60 the member will be thrown upward causing the movable member to be thrown into its normal position, and means comprising a movable weight carried by the movable member for maintaining said member in 65 either a set or normal position.

4. In a toy bowling device, the combination with a suitable supporting framework, a pendant member mounted therein, and de- signed to be operated by a rolled ball, a 70 slidable rod located in the path of the pend- ant member, a movable member as a ball de- signed to be operated by the slidable rod for moving the movable member into its normal position, means for resetting the movable member comprising a rod having 75 an arm thereon and located back of the piv- otal connection of the movable member for setting the same, whereby when the pendant member is oscillated the movable member will be tilted into its normal position, said 80 movable member having a rolling weight for tilting the same as the weight passes its pivotal connection.

5. A device of the kind described, comprising a frame work, tilttable members sup- 85 ported therein and adapted to remain in either substantially a horizontal or vertical position, said members being in the horizontal positions when set, means for tilting the members into the vertical positions, means for retaining the members in 90 either positions.

6. In a toy device of the kind described, the combination, of a frame construction, a tilttable member mounted therein, means for 95 tilting the member including a freely sus- pended pendant member designed to be struck by a rolled ball, and operative means including a sliding rod between the pendant member and the tilttable member.

7. A toy comprising a frame-work, a tilt- able member mounted therein, means for re- taining it in a slightly inclined or a nearly horizontal position, means for moving the member into nearly a vertical position, and including a pendant device designed to be struck by a rolled ball, a freely slidable, mov- able rod between the said device and the 105 tilttable member for transmitting the blow received by the pendant device to the tilttable member for causing the tilttable member to 110 assume the vertical position.

8. In a toy bowling device, a frame con- struction, weighted tilttable members therein and normally disposed in a slightly inclined or nearly horizontal position, but adapted by reason of the weight to assume substan- tially a vertical position and mean for sim- ultaneously moving all of the members into 115 their original inclined positions.

9. In a toy bowling device, a frame con- struction, overweighted tilttable members therein and normally disposed in an in- clined and nearly horizontal position, but adapted to assume substantially a vertical 125 position, said weight being a movable one, and means for simultaneously moving all of the members into their original inclined position comprising a rod, arms thereon for engaging all of the members for moving the 130

same from the vertical to an inclined position.

10. In a toy device, a supporting framework, a tilttable member supported thereby, 5 means comprising a freely slideable rod for tilting the member, and means for moving the slideable rod.

11. A toy of the kind described having in combination an overweighted tilttable member, a freely slideable rod for operating the member, a freely suspended pendant member for operating the rod.

12. A toy of the kind described comprising a supporting frame, overweighted tilttable members therein, means for tilting the same comprising a member movable relative to the tilttable member, means for returning the same to their original position comprising a rotatable rod having arms thereon for

engaging the short arm of the tilttable members whereby when the rod is rotated the overweighted members will be returned to their original positions.

13. In a toy device, as described, the combination, of a frame, a member pivotally supported therein and having arms of different lengths, a movable element on the pivotally supported member to cause the pivotally supported member to tilt about its pivot, and a slideable member for imparting an initial movement to the member for causing the movable element to tilt said member.

14. In a toy device of the kind described, a tilttable member, means for tilting the same comprising a freely slideable rod and a freely suspended pendant member arranged to strike one end of the rod, as described.
